UNITED STATES PATENT OFFICE.

MICHAEL F. SCALLEY, OF MIDDLETOWN, NEW YORK, ASSIGNOR TO SAFETY WATER GAUGE COMPANY, OF MIDDLETOWN, NEW YORK, A PARTNERSHIP CONSISTING OF MICHAEL F. SCALLEY AND SUSIE F. TUTHILL.

LIQUID GAUGE FOR BOILERS AND THE LIKE.

Application filed June 21, 1922. Serial No. 569,808.

To all whom it may concern:

Be it known that I, MICHAEL F. SCALLEY, a citizen of the United States, and resident of Middletown, in the county of Orange 5 and State of New York, have invented certain new and useful Improvements in Liquid Gauges for Boilers and the like, of which the following is a specification, reference being had therein to the accompanying 10 drawing.

Among the objects of this invention are:

Providing magnifying sight glasses having their curved surfaces at some distance from all their margins and between the 15 planes of the inner and outer surfaces of plane surrounding portions; keeping the temperature of the devices low through to avoid precipitation of solids therein; guarding against harm should the glass portions 20 break; and arranging the parts, all having other offices, to serve as radiating surfaces while exposed to air freely circulating over said parts.

In the accompanying drawings,

25 Fig. 1 is a view showing one of two similar broad faces of the entire apparatus.

Fig. 2 is a section on the line 2—2, Fig. 1.

Fig. 3 is a section on the line 3—3, Fig. 1.

30 Fig. 4 is a section on the line 4—4, Fig. 1.

Fig. 5 shows a broad face of a central water channel plate.

Fig. 6 shows similarly the inner face of one of two like glass bars which close a slot in the said plate.

35 Fig. 7 is a corresponding view of the interior of one of the halves of a metal casing.

In these figures, 10 represents a heavy, elongated metal plate having a central slot opening 11 laterally closed but provided

40 with water-admitting openings 12 at its ends, respectively, threaded to receive common coupling pipes 13. The plate has bolt holes spaced at short intervals around its perimeter, preferably in lugs 14, and the

45 central portion of each broad face of the plate is slightly depressed to form a plane sunken surface 15. Upon each broad face of this plate is placed a suitable packing sheet 16 upon which rests a very heavy glass

50 bar 17 which has the general contour of the plate, and is cylindrically concave, over the slot at 15 while in the plane area surrounding this depression is an endless small groove 19 to receive a narrow packing 20 which is

preferably carried by the packing sheet 16 55 lying under the glass bar upon the central plate. Each bar 17 has that face which is opposite the said cylindrically concave portion depressed to form below the general plane of that face a cylindrically convex rib 60 aligning with the slot 11 in the metal plate 10. If both glass bars are firmly clamped upon the metal plate 10, they close the slot therein, laterally, forming a water chamber into the ends of which the pipes 65 13 open.

The devices thus far described are enclosed in a strong metal casing consisting of oppositely turned, thin, marginally separated halves 21, 22 of cup-like form, each 70 having a central slot 23 registering with the slot 11 and surrounded by a plane area resting upon the marginal portion of the corresponding glass bar. Each casing half has spaced perforated lugs 24 registering 75 with the holes 14 in the plate 10. Bolts 26 bind all the parts together and the meeting faces of the casing halves, glass bars, and plate 10 being accurately plane and without projections, the bolts exert simply crushing force, without leverage at any point, and the glass is rarely or never broken. At the same time, should the glass break, the cup-like halves prevent any probable injury by 80 fragments. Thin packing is ordinarily used 85 to allow the infinitesimal variations due to changing temperature.

When the water chamber needs cleaning, the steam or the like being cut off, a simple wrench serves to remove the nuts allowing 90 all the parts to be separated and reassembled, even by non-mechanical persons, it being impossible to go astray.

It will be observed that aside from packing, connecting adjuncts and clamping bolts, 95 which are all alike, the entire apparatus consists of but five pieces.

Obviously, the water column is visible from either side, e. g., by the engineer and fireman, whether the light comes from one 100 side or the other.

Because a raised rib on the glass bar compels a laborious task of trying to form around the entire rib an accurately plane surface—within, perhaps, a thousandth of 105 an inch,—this with the bars made in this country and those made abroad, has not proved practicable, since such bars very

often crack. By sinking the rib, in molding the bar, the bar has two plane surfaces which can be easily and cheaply ground with almost mathematical exactness. In fact the breakage mentioned has been substantially eliminated.

The grinding of the plane contacting surfaces while permitting rapid and accurate work, does not injure the curved intermediate portions. Moreover, parallelism of the opposite contacting surfaces is assured. Due to this arrangement of parts, the pressure of the cups 21, 22 is maintained uniformly upon the outer portion of the glass while no stress is put upon the inner visible portion.

For keeping down the temperature in the chamber between the glass bars, the passages leading to and from that chamber are made of small diameter with respect to the cross-section of the chamber, and the most of the plate including its lugs and coupling portions as well as the separated halves of the casing with their lugs and the bolts give a relatively large radiating surface which keeps the temperature of the small amount of fluid admitted to the chamber far below the temperature at which deposition occurs.

30. What I claim is:—

1. In a gauge of the class described, the combination with a thick, elongated, flat metal plate recessed longitudinally at some distance from all its margins, provided with outwardly extending passages at the ends of the recess, respectively, and with terminal devices for connecting it with fluid conduits; of a transparent bar on one face of the plate covering and closing the slot; a metal casing enclosing the body of the plate and the bar, spaced from the margins of both plate and bar, and laterally open to allow free circulation of atmospheric air in the intervening space; numerous heat radiating lugs projecting into said space from adjacent metal portions of the structure; and means for binding together the plate, bar and casing.

2. A sight-glass bar having two opposite faces with their marginal portions in parallel planes and surrounding central magnifying portions lying wholly between said planes, whereby said bar may be readily and accurately ground with all parts of the marginal portions of each face plane

and precisely parallel to the corresponding portions of the opposite face.

3. The combination with a thick broad plate with a central slot and apertures leading into the ends of the slot, respectively, of numerous heat radiating lugs extending from the margins of the plate and perforated to receive binding bolts, plane sight-glass bars closing the slot on opposite sides, respectively, of the plate, a casing of metal composed of two marginally separated, oppositely turned, centrally slotted, cup-like halves enclosing said plate and glasses, spaced from the lateral margins of both, and at the margins of their slots engaging the bars, numerous perforated heat-radiating lugs projecting from the casing walls into the space between said walls and the edges of the plate and bars, and bolts passing through said perforations and binding the parts together, whereby atmospheric air circulates freely over approximately the entire surfaces of the bars and specially provided radiating surfaces of the metal portions.

4. In devices of the class described, the combination with a central gauge plate having a central chamber, magnifying sight glasses on opposite sides of said plate, each of said sight glasses having two opposite faces with their marginal portions in parallel planes and surrounding central magnifying portions lying wholly between the planes, of a casing having marginally separated, oppositely turned, cup-like halves embracing the sight glasses and means for binding the parts together.

5. In a gauge of the class described, the combination with a flat metal plate having outwardly extending heat radiating lugs, an elongated recess extending through the same and outwardly extending fluid passages at the ends of said recess, of a sight glass on one face of the plate covering and closing said recess, of a sight glass having two opposite faces with their marginal portions in parallel planes and surrounding central magnifying portions lying wholly between said planes closing said recess in the face of the plate opposite said first mentioned sight glass, and means for binding together the plate and sight glasses.

In testimony whereof I hereunto affix my signature.

MICHAEL F. SCALLEY.
